[57] CLAIM

The ornamental design for an electric moustache and beard trimmer or similar article, as shown and described.

DESCRIPTION

FIG. 1 is a front elevational view of an electric moustache and beard trimmer showing my new design.

FIG. 2 is a left side elevational view; the opposite or right side being a mirror image of the side shown.

FIG. 3 is a rear elevational view.

FIG. 4 is a top plan view.

FIG. 5 is a bottom plan view.
